US00D930608S

(12) **United States Design Patent** (10) **Patent No.:** **US D930,608 S**
(45) **Date of Patent:** **** Sep. 14, 2021**

(54) **SMART PHONE**

(71) Applicant: **Lenovo (Beijing) Co., Ltd.**, Beijing (CN)

(72) Inventor: **Jingjia Li**, Beijing (CN)

(73) Assignee: **Lenovo (Beijing) Co., Ltd.**, Beijing (CN)

(**) Term: **15 Years**

(21) Appl. No.: **35/508,333**

(22) Filed: **Aug. 15, 2019**

(80) **Hague Agreement Data**

Int. Filing Date: **Aug. 15, 2019**

Int. Reg. No.: **DM/205183**

Int. Reg. Date: **Aug. 15, 2019**

Int. Reg. Pub. Date: **Jan. 17, 2020**

(30) **Foreign Application Priority Data**

Feb. 15, 2019 (CN) 201930065561.3

(51) **LOC (13) Cl.** **14-03**

(52) **U.S. Cl.**

USPC ..... **D14/138 C**
